UNITED STATES PATENT OFFICE.

CHARLES A. TATUM, OF NEW YORK, N. Y., ASSIGNOR TO WHITALL TATUM COMPANY, OF NEW YORK, N. Y., A CORPORATION OF NEW JERSEY.

STOPPER FOR RECEPTACLES.

SPECIFICATION forming part of Letters Patent No. 731,523, dated June 23, 1903.

Application filed April 14, 1903. Serial No. 152,559. (No model.)

To all whom it may concern:

Be it known that I, CHARLES A. TATUM, a citizen of the United States, and a resident of the borough of Manhattan, city, county, and State of New York, have invented certain new and useful Improvements in Stoppers for Receptacles, of which the following is a specification.

My invention relates to means for closing the outlet of a receptacle, and has been devised particularly for use in conjunction with tooth-powder receptacles.

The object is to provide a simple device which in one position will effectively close the outlet of the receptacle and in another position will allow the contents to be poured or shaken out.

I prefer to construct my invention as a part of or an attachment to a stopper, so that the invention may be readily applied to various receptacles.

In the accompanying drawings I have illustrated two forms of my invention, Figure 1 being a sectional elevation on line 1 1 of Fig. 3, Fig. 2 a side elevation, and Fig. 3 a plan, of one form of my invention, while Fig. 4 is a side elevation of the other form, with parts in section.

In Fig. 1, A indicates the mouth of the bottle or other receptacle containing tooth-powder or the like. The stopper consists of a tube B, having a flange B' to fit on the end of the bottle and surrounded at its inner portion—that is, below the flange B'—with a gasket C, which is generally made of cork, although rubber or any other material might be employed that is adapted to produce a tight joint. Above the flange B' there is pivoted to the tube B, on the outside thereof, an elastic arm D, provided with a cap D', adapted to close the outlet of the tube B. This cap is preferably dished upon the surface that is adapted to engage the outlet, so that it may be locked in position when engaged with said outlet. The pivot of the arm D may be formed by a screw E. On the side of the cap D' opposite to that from which the arm D extends I have provided a handle D² to facilitate swinging the arm aside when desired. It will be understood that in the normal position the cap D' closes the outlet of

the tube D, and the contents of the receptacle cannot escape. When the arm D and the cap D' are swung aside, as indicated by dotted lines in Fig. 2, the outlet is cleared, so that the contents may be poured or shaken out of the receptacle.

In Fig. 4 the handle portion D², which projects from the cap D' at the side opposite to the arm D, has been lengthened and brought down against the side of the tube, to which it is pivoted, as by a screw E', located in alignment with the screw E—that is, in this case the structure is entirely symmetrical and the handle portion D² is elastic and corresponds exactly to the arm D. The operation and advantages of this form of my invention are the same as those described with reference to Figs. 1 to 3.

What I claim as new, and desire to secure by Letters Patent, is—

1. A stopper for receptacles, comprising a tube provided with a flange between its ends, a gasket surrounding said tube on one side of the flange, and a spring-arm pivoted to the tube on the other side of the flange and provided with a cap adapted to close the outlet of the tube.

2. A stopper for receptacles, comprising a tube having a flange between its ends, a gasket surrounding the tube at one side of said flange, an elastic arm pivoted to the tube at the other side of the flange and carrying a cap adapted to close the outlet of the tube, and a handle projecting from that side of the cap which is opposite to said arm.

3. A stopper for receptacles, comprising a tube, a spring-arm pivoted to said tube about an axis transverse to that of the tube and carrying a cap adapted to close the outlet of the tube.

4. The combination with a tube forming an outlet for a receptacle, of a spring-arm pivoted to said tube about an axis transverse to that of the tube and provided with a cap adapted to close the outlet of the tube.

5. The combination with a tube forming an outlet for a receptacle, of a spring-arm pivoted to said tube about an axis transverse to that of the tube, a cap carried by said arm and adapted to close the outlet of the tube, and a handle projecting from the cap at the

side opposite to that which is connected with said arm.

6. The combination with a tube forming an outlet for a receptacle, of an arm pivoted to said tube about an axis transverse to that of the tube, and carrying a dished cap adapted to close the outlet of the tube.

7. The combination with a tube forming an outlet for a receptacle, of an arm pivoted to said tube about an axis transverse to that of the tube, and carrying a cap adapted to close

the outlet of the tube, and a handle portion extending from the cap on the side opposite to said arm and pivoted to the tube.

In testimony whereof I have signed my name to this specification in the presence of two subscribing witnesses.

CHARLES A. TATUM.
